UNITED STATES PATENT OFFICE.

ANDREW G. CLUNE, OF NEW YORK, N. Y., AND ISRAEL V. EDGERTON, OF OAK PARK,
ILLINOIS.

DESIGN FOR A TAIL-LIGHT FRONT.

Application filed August 15, 1923. Serial No. 7,016. Term of patent 3½ years.

To all whom it may concern:

Be it known that we, ANDREW G. CLUNE and ISRAEL V. EDGERTON, citizens of the United States, and residents of New York, county of New York, and State of New York, and Oak Park, county of Cook, State of Illinois, respectively, have invented a new, original, and ornamental Design for Tail-Light Fronts, of which the following is a

specification, reference being had to the accompanying drawings, forming part thereof.

The figure is a face view of a tail light, showing our new design.

We claim:

The ornamental design for a tail light front, as shown.

ANDREW G. CLUNE.

ISRAEL V. EDGERTON.
